DESIGN FOR A CASKET CASE

Raymond Larson, Chicago, Ill., assignor to Central Metallic Casket Co., Chicago, Ill., a corporation of Illinois

Application November 6, 1936, Serial No. 65,743

Term of patent 7 years

To all whom it may concern:

Be it known that I, Raymond Larson, a citizen of the United States, residing at 2207 North Lamon Avenue, Chicago, in the county of Cook and State of Illinois, have invented a new, original, and ornamental Design for a Casket Case, of which the following is a specification, reference being had to the accompanying drawing, forming part thereof:

Fig. 1 is a plan view of a casket case embodying my new design;

Fig. 2 is a side elevation of same;
Fig. 3 is an end elevation of same, and
Fig. 4 is a fragmentary cross-section through the case wall.

I claim:

The ornamental design for a casket case, as shown.

RAYMOND LARSON.
